UNITED STATES PATENT OFFICE.

GEORGE S. HILTZ, OF NEW YORK, N. Y.

INKING MECHANISM FOR PRINTING-TELEGRAPH RECEIVERS.

1,313,295.

Specification of Letters Patent.

Patented Aug. 19, 1919.

Application filed July 21, 1916. Serial No. 110,451.

To all whom it may concern:

Be it known that I, GEORGE S. HILTZ, a citizen of the United States, residing at New York, in the county of Kings and State 5 of New York, have invented certain new and useful Improvements in Inking Mechanism for Printing-Telegraph Receivers, of which the following is a full, clear, and exact description.

10 The invention which forms the subject of this application relates to inking mechanism for printing telegraph receivers or "tickers," and in its preferred form is a species of the generic invention described and 15 claimed in my prior Patent No. 1,086,049, dated February 3, 1914. Its chief object is to provide a mechanism which shall require very little power for operation and which will apply the ink more evenly across the 20 type-wheel inking-roller. To these and other ends the invention consists in the novel features of construction and combinations of elements hereafter described.

One form of the invention is illustrated 25 in the accompanying drawing, in which—

Figure 1 is a side view of the inking mechanism, showing the rotary type wheel, the inking roller in rolling contact therewith, the stationary ink reservoir, and the 30 movable doctor roll for taking ink from the reservoir and applying it to the inking roller.

Fig. 2 is a plan view of the same, showing also the means provided to reciprocate the 35 inking roll axially.

Fig. 3 is a detail side view showing the doctor roll in ink-receiving contact with ink-supplying device, in the present instance a fibrous "wick" or brush, connected with the 40 ink reservoir.

The type "wheel," composed of two type disks 10, is fixed on a shaft 11 which is rotated, by gears 12, 13, under the control of an "escapement," not shown. The gear 13, 45 loose on shaft 14, is driven by frictional connection with one end of a spiral spring (not shown) in the barrel 15. The other end of the spring is attached to the shaft 14, and the latter is rotated (at each printing operation) to tension the spring by mechanism 50 fully described in my prior patent, above mentioned, said mechanism including a ratchet 16. The shaft and ratchet are numbered 22 and 25, respectively, in the patent 55 referred to. Fixed on the shaft is a fly wheel 17.

The inking roll 18, in rolling contact with the type wheel, is rotatably mounted in the arms of a U-shaped frame 19 pivoted loosely on a short shaft 20, parallel to the axis of 60 shaft 14; the frame being so proportioned as to let the roll bear on the type wheel with a pressure which is light but at the same time sufficient to afford adequate inking of the type, as will be readily understood. The 65 frame mentioned is also capable of sliding motion longitudinally of the supporting shaft, and is actuated by a cam 21, fixed on the shaft and having two inclined faces co-operating with fingers or pins 22 extending 70 inwardly from the two sides of the frame. The shaft and cam are rotated by means described hereinafter.

The tubular ink-reservoir 23 is parallel to 75 and above the inking roller 18, and is provided, above the center of the roller, with a fibrous brush or wick 24, supplied with ink from inside the reservoir by capillary attraction. The reservoir is filled through a small funnel 25.

Between the inking brush 24 and the inking roller 18 is a light doctor roll 26, pivoted to rotate freely on a stem 27 fixed in the outer end of the horizontal arm of a bell-crank lever 28 fulcrumed on a stud 29 85 projecting from a bracket 30 on one of the side frames 30^a of the machine. The depending arm of the bell-crank is provided with a long finger 31 extending into the path of a cam-stud 32 on the adjacent side 90 of the fly wheel 17. Then each time the stud 32, revolving about the axis of shaft 14 in the direction of the arrow, engages the finger, the bell-crank lever will be 95 swung clockwise, thereby bringing the doctor roll 26 into contact with the ink-saturated brush 24. When the stud passes the 100 pin the bell-crank swings back, bringing the doctor roll again into rolling contact with the inking roller 18, so that as the latter rotates and slides axially the ink received by the doctor roll from the brush will be applied to and be distributed over the inking roller.

If the ink reservoir 23 is more than half 105 filled with ink and the machine happens to be turned on its side for any length of time, as is liable to be the case when it is carried from one place to another, the ink may run out of the filling funnel 25. Any kind of a 110 stopper for the latter inevitably becomes smeared with ink and is therefore objection-

able. Accordingly I provide a normally empty reservoir into which the ink from the full reservoir will drain when the machine is turned on either side. Such a reservoir is shown at 23^a, in the form of a closed tube arranged above and parallel to the main reservoir and provided with ports 23^b, 23^c, (shown in dotted lines) at its ends to communicate with the former. Then if 10 the machine is turned on its side the surplus ink will run slowly into reservoir 23^a through the lower of the two ports while the air passes out through the upper into the main reservoir. It will be understood 15 that the ink is thick or viscous in consistency.

Depending from the bell-crank lever 28 is a hook-pawl 33, coöperating with a small ratchet wheel 34 on the cam shaft 20 and held in engagement with the ratchet by 20 gravity. The oscillations imparted to the bell-crank by the cam-stud 32, as described above, raises and lowers the pawl and so rotates the cam shaft and the cam 21, thereby shifting the carrier or frame 19 and the inking roller 18 carried by the former.

It is to be understood that the invention is not limited to the specific construction herein illustrated and described, but can be embodied in other forms without departure 30 from its proper spirit.

I claim:

1. In an inking mechanism for printing

telegraph receivers, in combination, a rotary type wheel, an axially shiftable inking 35 roller in rolling contact with the type wheel, an ink reservoir having an ink-supplying device adjacent to the inking roller, a doctor roll in rolling contact with the inking roller, a lever carrying the doctor roll, 40 means for rocking the lever periodically to carry the doctor roll into ink-receiving contact with the ink-supplying device, a cam associated with the inking roller to shift the same axially, and means actuated by 45 the said lever to actuate the cam and thereby shift the inking roller.

2. In an inking mechanism for printing telegraph receivers, in combination, a rotary type wheel, an axially shiftable inking 50 roller in rolling contact with the type wheel, an ink reservoir having an ink-supplying device adjacent to the inking roller, a doctor roll in rolling contact with the inking roller, a lever carrying the doctor roll, 55 and adapted to shift the same into ink-receiving contact with said ink-supplying device, a cam shaft having a cam connected with the inking roller to shift the same axially, a ratchet on the cam shaft, a pawl 60 carried by the lever and engaging the ratchet to rotate the same, and means to actuate the lever periodically.

In testimony whereof I hereunto affix my signature.

GEORGE S. HILTZ.
